PIEZOELECTRIC CRYSTAL

Augustus B. Tripp, Schenectady, N. Y., assignor
to General Electric Company, a corporation of
New York

Application April 27, 1935, Serial No. 18,584.

7 Claims. (Cl. 171—327)

My invention relates to piezo electric crystals and methods and means for adjusting the frequency thereof.

It has for one of its objects to increase the facility with which the frequency of piezo electric crystals is adjusted.

My invention relates more particularly to piezo electric crystals and crystal apparatus disclosed in my copending application Serial No. 712,562, filed February 23, 1934, and entitled Piezo electric crystals, of which my present application is a continuation-in-part.

In that application a piezo electric crystal is shown which is supported horizontally between two spaced electrodes and held in place on one of said electrodes by a pin projecting from the electrode into a minute hole in the crystal. This hole is placed at a nodal point of the mechanical vibration of the crystal whereby the pin has a minimum of effect upon the crystal frequency.

It has been found that this hole, though situated at a nodal point of the mechanical vibration of the crystal, affords a convenient means for adjusting the frequency of the crystal, and that by a very slight grinding at an edge of the hole, as by inserting the pointed end of a wire into the hole and rotating the wire between the fingers, the frequency of the crystal may be lowered over a considerable range.

Thus in the use of piezo electric crystals and apparatus of the type referred to if it be found that the crystal after proper adjustment of the electrodes of the cell in which it operates, does not produce the desired frequency, the crystal may be removed therefrom and ground slightly by a pin rolled between the fingers in the manner indicated. If upon reinserting the crystal in the cell it be found that the frequency has been lowered too much by this grinding a subsequent adjustment may be made by adjusting the spacing between the crystal electrodes. Thus accurate adjustment of the crystal frequency may be effected with great facility by this alternate grinding at the hole with a pin and adjustment of the crystal electrode.

The novel features which I believe to be characteristic of my invention are set forth with particularity in the appended claims. My invention itself, however, together with further objects and advantages thereof, may best be understood by reference to the following description taken in connection with the accompanying drawing in which Fig. 1 is a cross-sectional view of a crystal cell and crystal utilized in accordance with my invention; Fig. 2 is an exploded view of the crystal

cell, and Fig. 3 is illustrative of the method of grinding of the crystal.

Referring to Fig. 1, the side walls of the crystal cell edgewise of the crystal are formed by the member 1 comprising a suitable insulating material, such as a phenolic condensation product, and which is shaped to enclose a space of parallelopiped form. One electrode of the crystal cell comprises a conducting member 2 which is attached to the lower surface of the member 1, the opposite electrode comprising a conducting member 3 which is suspended from the upper wall of the crystal cell. This upper wall of the crystal cell comprises a plate 4, which may be either conducting, or non-conducting, attached to the member 1 and to which a conducting internally screw-threaded collar 5 is attached, this collar having a shoulder 6 which abuts against the lower surface of the member 4, and a neck, which projects just through the member 4. This collar is secured in the opening formed in the member 4 by peening the upper outer edge of the neck. The body of the collar projects a considerable distance below the lower surface of the member 4. The electrode member 3 is externally screw-threaded into the collar 5 and has holes 7 formed therein to receive a pronged wrench whereby it may be rotated for vertical adjustment, as for example to adjust the air gap between the electrode and crystal.

The piezo electric crystal 8 is mounted between the two electrodes and has a minute, preferably cylindrical, hole 9 formed at the center, or at a nodal point of mechanical vibration thereof. This hole is in line with a somewhat smaller hole in the lower electrode. The crystal is held in position on the lower electrode by means of a pin 10 having a cylindrical head which is in the hole in the crystal, and the body of which projects into the hole in the lower electrode. This pin may be of any suitable material, preferably metal.

This arrangement of members is best illustrated in Fig. 2. The upper wall 4 of the crystal cell, having the collar 5 peened therein is provided with screw holes 11 in alignment with corresponding holes 12 in the member 1, similar holes 13 being provided in the lower crystal electrode 2 whereby those members are attached by means of screws to the broadside faces of the member 1. The lower portion of the member 3 is seen to be of somewhat larger diameter than the upper screw-threaded portion thereof and is of sufficient diameter to present a broadside surface which substantially covers or exceeds the surface of the crystal.

It is necessary in a device of this kind, particu-

larly when used on aircraft, to restrain the crystal 8 against longitudinal movement within its enclosure thereby to prevent vibrating surfaces of the crystal from coming into contact with the fixed members of the crystal cell. It has been found that the pin 10 arranged in the minute opening at the nodal point of the crystal is a very advantageous manner of effecting this result. The hole in the crystal may be so small that it has little or no effect upon the characteristics of the crystal, such as the temperature coefficient, although it has been found that it reduces the crystal frequency. The head of the pin 10 is of slightly smaller diameter than the hole 9 so that a slight clearance is present about the head to avoid cracking of the crystal due to changes in temperature. This head is also of about one-half the thickness of the crystal so that it has practically no effect upon the operation of the crystal.

The shortest internal dimension of the crystal cell is longer than the longest dimension of the crystal so that no part of the crystal ever touches a side wall of the cell.

Fig. 3 illustrates more particularly the method of adjusting the frequency of the crystal. The crystal 8 is removed from the cell in which it is employed, laid upon a plate 14, and the point of a small pin 15 inserted in the hole 9. By rolling the pin 15 between the fingers the upper edge of the hole 9 may be slightly ground. This pin may, for example, comprise the sharpened end of a piece of wire of larger diameter than the hole, which ordinarily is of about a millimeter and a half in diameter. Carborundum and water may, if desired, be used as an abrasive. This grinding may be sufficient substantially to lower the frequency of the crystal. The crystal may then be reinserted in the cell and if the frequency be too low the final adjustment may be made by rotating the electrode 3, thereby to adjust the air gap between the crystal and electrode.

The crystals in connection with which my present invention may be employed may be adapted for operation at any desired frequency including frequencies extending from 100 kilocycles to 15,000 kilocycles or higher.

It will be understood that my invention may be used in connection with crystals of X, Y, and other desired cuts and that they may be of rectangular, disk, triangular or other geometrical shape.

What I claim as new and desire to secure by Letters Patent of the United States, is:

1. The method of lowering the frequency of a piezo electric crystal having a hole therein which includes grinding at the edges of the hole. 5

2. The method of lowering the frequency of a piezo electric crystal having a hole therein at a nodal point of mechanical vibration which includes grinding at the edges of the hole. 10

3. The method of lowering the frequency of a piezo electric crystal having a minute hole therein which includes inserting in said hole an instrument so shaped relative to the hole that it rides upon the edges of the hole at the entrance 15 end of the crystal, and rotating said instrument to wear away said edge.

4. The method of adjusting the frequency of a piezo electric crystal having a minute hole therein whereby it is retained in position between two 20 variably spaced electrodes which includes alternately grinding at an edge of said hole, and adjusting the spacing between said electrodes until the desired frequency is obtained.

5. The method of adjusting the frequency of a piezo electric crystal having a minute hole therein whereby it is retained in position between two 25 variably spaced electrodes, which includes rough adjusting said frequency by removing the crystal from said electrodes and grinding at the edge of 30 said hole until a frequency approximating the desired frequency is obtained, and then replacing the crystal between said electrodes and adjusting the spacing between the electrodes until the desired frequency is obtained. 35

6. The method of lowering the natural frequency of a piezo electric crystal having a nodal point of mechanical vibration which includes grinding off a portion of the crystal in proximity to said nodal point. 40

7. The method of adjusting the natural frequency of a piezo electric crystal which is retained in position between two variable spaced electrodes and which has a natural frequency of mechanical vibration which is higher than 45 that desired which includes alternately grinding off a portion of the crystal in proximity to a nodal point of mechanical vibration and adjusting the spacing between the electrodes until the desired frequency is obtained. 50
